W. H. MILLER

DRILLING MACHINE

Filed Jan. 21, 1926

UNITED STATES PATENT OFFICE.

WILLIAM H. MILLER, OF WICONISCO, PENNSYLVANIA.

DRILLING MACHINE.

Application filed January 21, 1926. Serial No. 82,705.

The invention relates to portable drilling machines, particularly adapted for use in connection with coal mine drills, and has for its object to provide a portable drilling machine, which is manually operated, and one wherein a rapid succession of percussive blows may be imparted on a drill simultaneously with a rotation of the drill, thereby insuring a rapid drilling operation.

10 A further object is to provide a portable drilling machine comprising a casing having rotatably mounted therein a drill carrying sleeve, which drill carrying sleeve, at its inner end is provided with a bevelled gear which meshes with a bevelled gear carried by an operating shaft to which an operating crank is connected. The operating shaft is provided with a star wheel having a plurality of curved arms, which curved arms 20 cooperate with a roller carried by a hammering member slidably mounted in the casing, and which hammering member is provided with oppositely extending guide lugs, one of which carries the roller, and which guide lugs are slidably mounted in bifurcated members formed by oppositely disposed arms of the casing sections.

25 A further object is to provide a shaft adjustably mounted in the hammering member, and extending into the gear carried sleeve and adapted to impart percussive blows on the drill and a coiled spring surrounding the shaft and interposed between the hammering member and the rear end of the casing. The adjusting of the hammering member on the shaft allows varying of the tension of the spring for varying the force of the blows imparted on the drill.

30 A further object is to provide a handle member at the rear end of the casing, which handle member may be used as a breast plate if desired.

35 A further object is to curve the arms of the star wheel on one of their sides so that the roller will easily ride thereover and to convex the opposite sides of the arms so that the roller will quickly drop in between the arms, thereby insuring a quick hammering action.

40 With the above and other objects in view the invention resides in the combination and arrangement of parts as hereinafter set forth, shown in the drawing, described and claimed, it being understood that changes in 45 the precise embodiment of the invention may be made within the scope of what is claimed

without departing from the spirit of the invention.

In the drawings:—

Figure 1 is a horizontal sectional view 60 through the portable hammer, parts being broken away to better show the structure.

Figure 2 is a sectional view taken on line 2—2 of Figure 1.

Referring to the drawing, the numeral 1 65 designates the casing of the portable hammer, which casing is formed from registering sections 2, which sections are provided with flanges 3, through which securing bolts 4 extend, whereby the sections can be separated so that access may be had to the interior of the machine. Casing 1 is provided with a restricted chamber 5 and an enlarged chamber 6, and the sections 2 of the casing are provided with spaced arms 7, which 70 when brought together when the sections are assembled form guide recesses 8 for the lugs 9, which guide the hammering member 10 during its reciprocation. One of the guide lugs 9 is provided with a roller 11 80 which is mounted on antifrictional bearings 12, and with which roller the curved arms 13 of a star wheel 14 cooperate during the rotation of the star wheel. The arms 13 are provided with curved surfaces 15 which during the rotation of the star wheel engage the roller 11 and force said roller and the hammering element 10 rearwardly. The opposite sides of the star wheel arms are curved, thereby allowing the roller 11 to quickly 85 drop between the arms so that the star wheel will not interfere with the forward movement of the hammering member 10. Extending longitudinally through the hammering member 10 is a shaft 16, which is held 90 in various adjusted positions by means of the set screws 17, and surrounding the shaft 16 and interposed between the rear end of the hammering member 10 and the rear wall 18 of the casing is a coiled spring 19, which 95 coiled spring imparts the forward movement on the hammering member 10 and causes the end 20 of the shaft 16 to impart a percussive blow on the rear end 21 of the drill 22 thereby insuring a hammering action on the 100 drill. Shaft 16 is slidably mounted in a bearing 23 formed by the casing sections 2 at the rear end thereof and in the bearing 24 of the rotatable sleeve 25, which is rotatably mounted in a bearing sleeve 26 between the forward ends of the casing sections 2, therefore it will be seen that the

shaft 6 is accurately guided during its reciprocation. By adjusting the hammering member 10 on the shaft 16 the expansive power of the coiled spring 19 may be varied for varying the force of the percussive blows of the shaft end 20 on the drill. In coal mining and in other drilling operations it is also desired to rotate the drill 22.

The rotation of the drill 22 is accomplished by means of a manually operated crank 27, which is carried by the outer end of an operating shaft 28, and which shaft 28 extends inwardly into the chamber 6, and has mounted thereon the star wheel 14 and a bevelled gear 29, which bevelled gear meshes with a bevelled gear 30 carried by the rotatable sleeve 25, therefore it will be seen that during the hammering operation on the drill, the drill will be simultaneously rotated, consequently a quick drilling operation is accomplished. The rear end of the casing 1 is provided with a breast plate 31, which may also be used as a handle member if desired. During a drilling operation the breast plate 31 is preferably placed against the chest and the operator grasps the operating crank 27 and rotates the same, which operation will rotate the sleeve 25 through the medium of the shaft 28 and bevelled gears 29 and 30, at the same time the star wheel 14 will cooperate with the roller 11 and force the hammering member 10 rearwardly thereby compressing the coiled spring 19, and when the hammering member 10 is released by the arms 13 of the star wheel, said coiled spring will force the hammering element forwardly so that the shaft end 20 will impart percussive blows on the drill.

From the above it will be seen that a portable drilling machine is provided which is manually operated, compact, positive in its operation and one wherein the working parts are entirely encased and protected from foreign matter, thereby insuring a positive operation at all times. It will also be seen that the casing sections when brought together form the bearings for the movable parts as well as the guide recesses 8.

The invention having been set forth what is claimed as new and useful is:—

1. A portable drilling machine comprising a casing; a drill receiving sleeve rotatably mounted in one end of the casing, a hammering shaft slidably mounted in the sleeve and adapted to cooperate with a drill in the sleeve, a hammering member adjustably mounted in the shaft, a coiled spring inter-

posed between the hammering member and one end of the casing, an operating shaft rotatably mounted in the casing to one side thereof, a gear carried by the rotatable sleeve, a gear carried by the operating shaft and meshing with the first mentioned gear and adapted to rotate the same, an operating crank carried by the operating shaft, a star wheel carried by the operating shaft, oppositely disposed guide lugs carried by the hammering member, a roller carried by one of said guide lugs and with which the star wheel cooperates, oppositely disposed arms carried by the casing and forming guide recesses for the lugs, said casing being formed from sections which when brought together form the bearings for the movable parts, said lug guide arms being carried by the sections of the casing and forming guide recesses when the sections are brought together.

2. The combination with a portable drilling machine comprising a casing having a hammering element slidably mounted therein and operable under and against the influence of an expansion spring, lugs carried by the hammering member and slidably mounted in recesses, a star wheel cooperating with one of said lugs whereby the hammering element is reciprocated, means for rotating said star wheel, said casing being formed from registering sections, said registering sections being provided with oppositely disposed arms, which when brought together form the guide recesses for the lugs.

3. A drilling machine comprising a sectional casing, a sleeve rotatably mounted in one end of said casing and adapted to receive a drilling tool therein, a shaft slidably mounted in the sleeve and in one end of the casing, a hammering member adjustably mounted on the shaft, a coiled spring surrounding the shaft and cooperating with the hammering member for forcing the same forwardly, oppositely disposed guide lugs carried by the hammering member and slidably mounted in guide recesses, a roller carried by one of said lugs, an operating shaft, a star wheel carried by the operating shaft and cooperating with the roller, a bevelled gear carried by the operating shaft, and a bevelled gear carried by the rotatable sleeve and meshing with the bevelled gear on the operating shaft.

In testimony whereof I hereunto affix my signature.

WILLIAM H. MILLER.
